ATTORNEYS

UNITED STATES PATENT OFFICE

EDWIN L. GRAUEL, OF CINCINNATI, OHIO

MATCH PACKAGE HOLDER

Application filed October 31, 1930. Serial No. 492,552.

My invention relates to match package holders, and particularly to holders adapted for use with match packages such as are disclosed in my co-pending applications Serial No. 483,049, filed September 19, 1930, and Serial No. 492,551, filed Sept. 19, 1930.

In my co-pending applications referred to, I have described several modifications in different types of match packages in which matches are retained with their heads extending within folded blanks, and with a cover member fitting over the folded blank and providing a safety package in which the matches are ignited by areas of fulminate arranged 15 at the withdrawal orifices in the packages.

It is the object of my invention to provide a holder for a series of match packages of the type aforementioned, in which the packages may be readily moved with a sliding motion 20 in between retaining side plates which will secure the package in position so that the matches may be withdrawn therefrom by a simple pulling movement exerted on the exposed ends of the matches.

25 It is a further object of my invention to provide a holder for match boxes in which the retaining plates of the individual package holders may be demountably arranged on a base so that the individual holders may be 30 readily removed for cleaning and other purposes.

It is a further object of my invention to provide a receptacle for used matches which forms part of the bracket device which retains 35 the individual package holders.

The above objects and other objects to which reference will be made in the ensuing disclosure, I accomplish by that certain combination and arrangement of parts of which 40 I have shown a preferred modification.

Referring to the drawings:—

Figure 1 is a front elevation of a preferred type of match package holder.

45 Figure 2 is a sectional view taken along the lines 2—2 in Figure 1.

Figure 3 is a side elevation of the holder shown in Figure 1.

Figure 4 is a perspective view of a mounting plate for the holder which will permit the

individual package holder to be slidably arranged thereon.

Figure 5 is a front elevation of a holder mounting plate adapted for use with the holder parts shown in Figure 4. 55

Figure 6 is a perspective view of a stove with the match package holder shown in Figures 1 and 3 mounted thereon.

Figure 7 is a front elevation of the dashboard of an automobile on which one of my preferred types of match package holders is mounted. 60

Referring first to Figures 2, 4 and 5, I have shown the mounting plate 1 which is of contoured formation, and has slots 2 therein for receiving the holder to be subsequently described. The mounting plate may have apertures 3 therein for the reception of bolts or screws to mount the plate on the wall of a stove, room or vehicle. The holder has a base plate 4 provided with tongues 5 which are received within the slots 2 in the mounting plate, and in the modification shown a receptacle 6 is provided for receiving burnt matches. 70

The individual match package holders 7 are provided with channeled tongues 8 which slidably engage the edges 9 of the holder plate 4 so that a desired number of individual package holders may be mounted on the 80 plate 4.

The holders have back walls 8a and side walls 8b spaced at their side edges and with their ends bent inwardly, as indicated at 8c, to prevent the packages from pulling out, but 85 allowing a space through which the ends of the matches within the packages extend.

The packages 10 have match ends 11 extending therefrom, so that when the packages are engaged within the resilient side plates they are held firmly therein and the matches may be readily withdrawn. 90

Other forms and arrangements of holders for match packages of the type described, in 95 which the packages are inserted with a sliding movement in between flexible retaining plates, and in which the insertion of a new package will push out an empty package, will readily occur to those skilled in the art with- 100

out departing from the principle of my invention.

Having thus described my invention, what I claim as new and desire to secure by Letters Patent is:—

1. An article of manufacture comprising a support, said support having united thereto a refuse compartment, and a holder rigidly held on said support to detachably receive, and to hold in a position of ready access, a packet of matches arranged to be ignited by withdrawal from said packet, said matches after ignition being depositable in said compartment, said holder comprising opposed spring leaves arranged for sidewise insertion of said packet whereby said leaves are spread apart while said holder is in place on said support, and having an opening at the top through which the said matches may project, and means on said holder for preventing the endwise withdrawal of said packet.
2. An article of manufacture comprising a support, said support having united thereto a refuse compartment, and a holder united to said support to detachably receive and to hold in a position of ready access, a packet of matches comprising a body portion with the ends of matches projecting therefrom, said packet arranged to ignite said matches as they are withdrawn, said holder comprising opposed spring leaves arranged for sidewise insertion of said packet, having an opening at the top through which said matches may project, and having turned over portions to engage the top of said packet to prevent the endwise withdrawal thereof.
3. An article of manufacture comprising a support, and a member detachably secured to said support, said member comprising a refuse compartment and at least one holder to detachably receive and to hold in a position of ready access, a packet of matches arranged to be ignitable by withdrawal from said packet, said matches after ignition being depositable in said compartment.
4. As a new article of manufacture, a supporting member against which a pull may be exerted, a refuse compartment associated with said supporting member, and at least one holder for a paper packet of matches arranged for ignition upon withdrawal from said packet, said holder also associated with said supporting member and comprising opposed resilient members adapted to exert sidewise pressure upon the top of said packet, and means to prevent the withdrawal of said packet from said holder in the direction in which said matches are withdrawn, said holder adapted to present said matches in a position for withdrawal.

EDWIN L. GRAUEL.
